(57) CLAIM

The ornamental design for a false eyelash case, as shown and described.

DESCRIPTION

FIG. 1 is a perspective view of a false eyelash case, showing my new design, shown in a closed position;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof, shown in open position;

FIG. 9 is a back perspective view thereof;

FIG. 10 is a front view thereof;

FIG. 11 is a back view thereof;

FIG. 12 is a left side thereof;

FIG. 13 is a right side view thereof;

FIG. 14 is a top view thereof;

FIG. 15 is a bottom view thereof; and,

FIG. 16 is a front perspective view thereof, shown in an environment of use.

In the drawings, the broken lines illustrate portions of the article which form no part of the claimed design. In FIG. 16, the broken lines showing a plurality of false eyelashes and eyelash adhesive accessories illustrate environmental subject matter only and form no part of the claimed design.

The word "Lash Story" is a Registered Trademark of HOUSE OF LASHES CORPORATION.

1 Claim, 11 Drawing Sheets
